VOLUME CONTROL IN RECEIVER SETS

Helmut Pitsch, Berlin-Steglitz, and Otto Tüzen, Berlin, Germany, assignors to Telefunken Gesellschaft für Drahtlose Telegraphie m. b. H., Berlin, Germany, a corporation of Germany

Application October 27, 1937, Serial No. 171,204
In Germany October 28, 1936

3 Claims. (Cl. 179—171)

In order to diminish non-linear harmonic distortion, in the presence of low volume, it has been suggested to increase the external resistance of the power tube of amplifying apparatus. According to the present invention, the external resistance serves solely for volume control with the simultaneous use of several other objects of the invention.

The aim of the invention is to create volume control means adapted to minimize distortion by the power tube regardless of position or adjustment. According to previous notions it has been held that if the volume or signal strength is controlled and regulated at the output end of a power tube the distortions are more pronounced than when the same action is produced at the input end of the power tube. However, as demonstrated by the invention even a reduction of the non-linear harmonic distortion is feasible if certain features and steps as here disclosed are simultaneously used.

The invention consists in varying the external resistance of a triode power tube being of suitable proportions so as to insure full driving range up to a point where grid current starts to flow, in such a way that the volume decreases with increase of the said resistance, and that at the same time the highest occurring grid alternating potential impressed upon the power tube is only so high, or the power tube of such dimensions, that an appreciable overloading owing to incipient grid current flow will not happen when the apparatus is adjusted to maximum sound volume, means being moreover provided to the end of stabilizing the mean grid alternating (signal) voltage (for instance, gain regulation or phonograph disks).

In the drawing, Figs. 1 and 2 are curved sheets used in explaining the invention and Fig. 3 is a schematic diagram of a radio receiver incorporating the features of the present invention.

By reference to Fig. 1 of the appended drawings it shall first be shown that in the presence of an increase of the external resistance (say, by an increase in the transformation ratio of the output transformer for a dynamic loudspeaker), the delivered power or sound volume will decrease in spite of unvaried grid alternating voltage. In the drawing is graphically illustrated the well-known family of curves showing the dependence of the plate current I_a upon the plate potential U_a of a triode (single-grid) type of tube. These various graphs apply to different grid potentials. Working characteristic A corresponds to the external resistance chosen of optimum

value to suit a driving range up to incipient grid current flow, for a given working point. The characteristic is chosen so steep that the working point will divide a given grid voltage range into two parts being as far as feasible equal.

With growth of external resistance the working characteristic A becomes less steep (A₁). Inasmuch as the triangles indicated in the drawing are a measure and criterion for the delivered power, it will be noted that with increase of external resistance, in spite of the same grid alternating potential, the volume will decrease. The prerequisite condition, namely, that the external resistance should then differ more widely from the internal resistance is automatically fulfilled, if the above rule of dimensioning the external resistance is satisfied, for modern radio tubes.

Figure 2 which shows the dependence of the power upon the non-linear harmonic distortion for increasing outer resistance (characteristics 1—3) makes it clear that the non-linear harmonic distortion decreases with increases in the external resistance.

The marked rise of the characteristic when getting into the hatched portions corresponds to the start of grid current flow. If the external resistance is not altered, one would get, say, from point a to point b as the signal voltage (grid alternating voltage) decreases. But if the volume is reduced by raising the value of the external resistance, one might get, say, to point c from point a, while yet the same volume (power) is obtained as at b, though with a non-linear distortion.

The risk of overload in this instance is not greater than for the maximum sound volume, with a resistance corresponding to graph 1, provided that the highest occurring signal voltage is only so high, or the power tube is so amply proportioned, that, even when the set is adjusted to maximum volume, no overload due to incipient grid current flow will occur. This can be seen also from Fig. 1 where the characteristic 0 corresponds roughly to the beginning of grid current. Another presupposition, according to a further feature and object of the invention as hereinbefore mentioned is that, for instance, by satisfactory volume control care has been taken so that the mean signal or grid alternating voltage will be constant so that the manually operated volume control, apart from the equalization of differences in modulation percentage of the various transmitter stations, serves solely for the adjustment of the set to the desired volume.

Application of this invention to pentodes is not

practicable for the reason that, inside a relatively large range of size of the external resistance, the power varies but little, but the non-linear harmonic distortion very markedly.

- 5 Where the present invention is carried into practice, the input tubes must be proportioned so generously that the distortions liable to arise in practice will be moderate even for maximum drive ranges.
- 10 It is to be noted that with an increase of the external resistance of the power tube, by raising the transformation ratio of the output transformer, say, by means of taps, the high-pitched notes will be somewhat weakened, though this 15 could be compensated by the aid of equalizer means.

Another manner adapted to regulate the outer resistance as shown in Fig. 2 is accomplished by connecting a resistance W in series with the loudspeaker coil. In this way the said drawback is obviated seeing that, upon rise of the loudspeaker resistance, for instance, for high notes, a larger share of the power applied to the series resistance W and the loudspeaker will go to the loudspeaker than is true for the low-pitched notes. On the other hand, by the use of a series resistance, the efficiency is impaired so that the external resistance, to obtain a certain volume reduction may rise somewhat less. The improvement of conditions regarding the non-linear harmonic distortion will then be correspondingly smaller, yet, it will nevertheless be present. By the way, the two ways and means adapted to volume control as just mentioned could also be used simultaneously.

The series resistance should preferably not be included in the output circuit of the power tube traversed by D. C. in order that the operating potentials of the power tube may not be unfavorably affected. It may also be noted that parallel connection of an ohmic resistance to the loudspeaker will not attain the aim and end of the invention, quite on the contrary.

In the exemplified embodiment Fig. 3, the portion of the receiver E located below the power tube is provided with fading compensator (avc) means with forward and backward action. The RF energy utilized for such control action, as will be seen, is rectified in rectifier G , the resultant avc potential being impressed upon a lower and a higher stage. The amplitude fed to the power tube may once for ever be adjusted to an optimum value by choosing corresponding dimensions for the coupling means.

The invention will be found useful also in AF amplifiers comprising means for gain regulation. In case of amplification for the playing of phonograph records, a limitation is imposed upon the amplitude alone on the ground that the sound volume produced by a record is unable to surpass certain values conditioned by a given groove or track width and a given gauge of the needle.

It is claimed:

- 65 1. In amplifying apparatus, a power tube having a cathode, a grid and an anode, an input cir-

cuit for said tube connected between the grid and cathode thereof, an output circuit connected between the anode and the cathode of the tube, a load, means for coupling the tube output circuit and the load, said means being arranged to 5 substantially match the impedance of the load to the impedance of the tube for maximum power transfer, a driving circuit for said tube coupled to the input circuit thereof said driving circuit including means for stabilizing the signal energy 10 impressed upon the input circuit of the tube and to limit its maximum amplitude to a value such that the highest occurring alternating current potential impressed upon the grid will not cause 15 grid current to flow at maximum power transfer between the tube output circuit and the load, and supplementary means for increasing the effective external plate circuit alternating current impedance of the tube to thereby reduce both 20 the non-linear distortion of the tube and the power transferred to said load.

2. In signalling apparatus, a power amplifier tube including a grid circuit and a plate circuit, a load, coupling between the plate circuit and the load including matching means adapted to 25 reflect into the tube circuit an impedance at least as high as the output impedance of said tube, a driving circuit for the tube coupled to the grid circuit thereof, said driving circuit including means for stabilizing the signal energy impressed upon the grid circuit of the power tube and limiting its maximum amplitude to a value such that the highest occurring alternating potential impressed upon the grid will not cause 30 grid current to flow at maximum power transfer between the plate circuit and the load, and a resistance in series with said load for increasing the effective external output circuit alternating current impedance of the tube to thereby provide for the simultaneous reduction of both the 35 non-linear distortion of the tube and the power delivered to the load.

3. In a signalling circuit, a power amplifier tube provided with a plate circuit including the primary winding of an output transformer, and a grid circuit, a driving circuit for said tube coupled to said grid circuit and including means for stabilizing the signal energy impressed upon the grid circuit and limiting its maximum amplitude to a value such that the highest occurring 45 alternating current impressed upon the grid circuit will not cause grid current to flow at maximum power transfer between the plate circuit and the load and said load in series connected across the secondary winding of said output 50 transformer, said transformer comprising a matching means arranged to reflect into the tube circuit an impedance at least as high as the output impedance of said tube, said variable resistor providing means for reducing both the 55 non-linear distortion of the tube and the power delivered by the tube to the load without varying any direct current operating potential applied to the tube.
